UNITED STATES PATENT OFFICE.

DENNY EDMUND WALSH, OF GRAND SALINE, TEXAS.

TAG-FASTENER.

1,103,853.

Specification of Letters Patent. Patented July 14, 1914.

Application filed December 12, 1913. Serial No. 806,254.

To all whom it may concern:

Be it known that I, DENNY EDMUND WALSH, a citizen of the United States of America, residing at Grand Saline, in the county of Van Zandt, in the State of Texas, have invented certain new and useful Improvements in Tag-Fasteners, whereof the following is a specification.

This invention relates to tag fasteners designed to be especially useful in large mercantile establishments conducting a mail order business in which a great multiplicity of packages are prepared for mailing by parcel post or otherwise.

The object of the invention is to provide a tag fastener of simple construction and trifling cost, which can be applied to the package with great rapidity and which will not easily become detached therefrom, thus economizing time of the mail order shipping clerks and insuring safety in the delivery of the package.

Figure 1 of the accompanying drawings represents a perspective view of a package to which a tag is secured by this improved tag fastener. Fig. 2 represents an enlarged side elevation of a tag fastener embodying one form of this invention showing a section of the tag attached at one end and a section of the binding cord of the package at the other end. Fig. 3 represents a side elevation of this improved tag in the first stage of the operation of hooking the fastener to the binding cord of a package, the looped hook of the fastener entering under said cord. Fig. 4 represents a side elevation thereof in which the looped hook of the fastener is passed under the cord a sufficient distance to lift the spring tongue. Fig. 5 represents an envelop tag usable as a substitute for the tag of Fig. 1 and adapted to contain an invoice of the contents of the package.

The same reference numbers indicate corresponding parts throughout the different figures.

This tag fastener 10 is composed of flat steel wire in one piece, said wire having more or less resilience.

This fastener comprises a shank 11 along its upper side, a spring tongue 12 along its lower side, a tag loop 13 at its inner end integral with said shank and tongue and a looped hook 15 at its outer end integral with said shank and adapted to engage the binding cord of the package. This looped hook 15 is formed by a primary return bend 16

forming a continuation of the shank 11 and a secondary return bend 17 forming a continuation of the return bend 16. This looped hook is disposed adjacent to the spring tongue 12 and projects laterally beyond said tongue. The secondary return bend is disposed on an incline and forms a looped bill which is at an acute angle to the shank and adapted to pass readily under a package binding cord in the normal position in which the tag fastener is grasped as indicated in Fig. 3. The end of the secondary return bend 17 is preferably folded forming a reinforced tip 18. The free end of the spring tongue 12 rests normally against the tip 18 of the looped hook 15 and yields automatically to permit the entrance of the fastening cords and acts as a lock against accidental release thereof.

This tag fastener is designed to be attached to an address tag 20 or other tag by passing the tongue 12 through the reinforced eyelet 21 of said tag and hanging the tag in the loop 13. The reinforced eyelet of the tag is preferably provided with a square opening 22. These two parts are designed to be united at the factory and sold together as an article of manufacture.

An envelop tag 30 adapted to contain an invoice or other papers and provided with a reinforced eyelet 21 may be substituted for the tag 20. The flattened wire in connection with the square opening of the reinforced eyelet tends to maintain the tag in proper position on the package.

In the use of this invention, the package 40 to be mailed or otherwise transmitted is provided with a binding cord 50 which is preferably passed around said package in different directions forming an intersecting junction 51. The package thus prepared is grasped in one hand and the tag 20 or 30 bearing the address and carrying the tag fastener 10 is grasped in the other hand. The looped hook 15 is then brought into contact with the cover or covering of the package 40 somewhat in advance of the binding cord 50, preferably adjacent to the junction 51 of said cord. Then the hand holding the tag and its fastener is given a quick jerk backward and the looped hook 15 passes under said cord 51 which is adjacent to and extends laterally beyond the spring tongue 12, said cord first riding over the return bend 17 of said hook as shown in Fig. 3, thence under the spring tongue 12, automatic-

cally lifting the latter after its engagement with said hook as shown in Fig. 4, and thence passing into the loop of said looped hook as shown in Fig. 2, the free end of the spring 5 tongue then springing back against the tip 18 of said looped hook and practically locking the cord within the fastener as shown in Fig. 2 or the junction 51 of cords within the fastener as shown in Fig. 1.

10 It is thus apparent that hundreds and thousands of address tags can be applied to packages by the aid of this fastener in a very short time.

I claim as my invention:

15 A tag fastener composed of wire in one piece and comprising a shank forming one side of the fastener, a spring tongue forming the opposite side thereof, a tag loop forming a continuation of said shank and tongue 20 and a looped hook adjacent to and extend-

ing laterally beyond said tongue and composed of a primary return bend integral with the opposite end of said shank and a secondary return bend in continuation of said primary return bend and disposed on 25 an incline and forming a looped bill disposed at an acute angle to said shank and adapted to pass in quick application under a package binding cord, the free end of said tongue normally resting on said secondary 30 return bend adjacent to the tip thereof, said inclined secondary bend forming in conjunction with said tongue a tapering mouth which insures the entrance of said cord into said looped hook.

DENNY EDMUND WALSHE.
